MEDICATION REMINDER CLOCK CASING

Roman J. Szalek, La Salle, Ill., assignor to General
Time Corporation, Stamford, Conn., a corporation
of Delaware

Filed Feb. 26, 1968, Ser. No. 10,723

Term of patent 14 years

U.S. Cl. D42—7
Int. Cl. D10—04

FIG. I

FIG.3

FIG.2

FIG. 4

FIG. 5

FIG. 1 is a perspective view of a medication reminder clock casing showing my new design;

FIG. 2 is a front elevational view;

FIG. 3 is a top plan view;

FIG. 4 is a left side elevational view, the side opposite (not shown) in plain and unornamented; and

FIG. 5 is a rear elevational view.

The broken line showings of a clock face and hands are for illustrative purposes only.

I claim:

The ornamental design for a medication reminder clock casing, substantially as shown and described.
